Patented Sept. 30, 1919.

UNITED STATES PATENT OFFICE.

MARCUS SHINSKIE, OF COALINGA, CALIFORNIA.

SUCKER-ROD MOUSETRAP.

1,317,229.

Specification of Letters Patent. Patented Sept. 30, 1919.

Application filed May 12, 1919. Serial No. 296,286.

To all whom it may concern:

Be it known that I, MARCUS SHINSKIE, a citizen of the United States, residing at Coalinga, in the county of Fresno and State of California, have invented certain new and useful Improvements in Sucker-Rod Mousetraps, of which the following is a specification.

My invention relates to oil-well pumping 10 outfits, and particularly to the class of fishing-tools for sucker-rods, and more especially to that type of tools known in the oil-fields as sucker-rod mouse-traps.

A common and well-known form of these 15 tools comprises an open ended barrel or cage adapted to fit and slip down in the well tubing and over the broken end of the sucker-rod string which is still attached to the pump plunger; and a gravity latch 20 fitted within the cage, which lifts to pass over the sucker-rod joint or coupling, and drops back again to engage under the lower shoulder of said coupling. Upon thus engaging, the tool with its suspended sucker- 25 rod, may be withdrawn from the well. In practice, the tool has several disadvantages. The most serious, perhaps, is the tendency of the gravity latch to catch and bind on the sucker-rod coupling in passing over it 30 and fail to drop back to proper engagement under the coupling; so that when lifted, the strain is so unequal that the tool either slips or is itself broken in one or more of its relatively narrow webs or ribs which surround the latch-seat.

One of the objects of my invention is to obviate this difficulty by applying to said latch a positive spring pressure, in order to insure its return to engagement; and to this 40 end my invention consists in the novel construction, arrangement and combination, of the cage, the latch, its hinge, and its controlling spring.

Another improvement of my invention 45 provides for a more ready finding by the tool and passing over the broken sucker-rod and its coupling; and to this end I make the lower extremity of the cage inclined to its axis, and bevel the inner surface of said extremity.

Another feature of novelty in the tool is 50 the intentional disposition of the suspending stem on the side of the cage in which lies the greatest opening around the latch-seat, thereby tending to equalize the weight and strains, and in bending said stem

slightly toward the axial line, thereby tending to balance the tool in suspension.

These improvements will now be made clear by the following description of the 60 tool, reference being had to the accompanying drawings, in which,

Figure 1 is an elevation, broken, of my sucker-rod, mouse-trap showing the latch 65 in its elevated position.

Fig. 2 is a vertical section, broken, of the same, on the line 2—2 of Fig. 1.

1 is the barrel or cage, open at both ends. Near its lower end it is formed with an opening 2 at one side, and with two narrow openings 3 at the other side. The base 2' of the opening 2 forms the major portion of the latch seat, while the bases 3' of the openings 3 form the seat for the latch forks.

4 is the latch, consisting of a forked plate, flat on its lower surface and so shaped on its upper surface, that when the latch is lifted to a vertical position, this latter surface will conform in general to 80 the curvature of the cage and present no obstruction to the slipping of the tool in the well tubing. This latch 4 is adapted to close down to a horizontal position on the seats 2' and 3', and to lift to a vertical position to lie in the wider opening 2.

In order to provide for detachably hinging the latch, so that it can be renewed when necessary, I secure to the cage by the screws 5, below the seat 2' a U-strap 6, one of the 90 legs of which lies inside the cage and the other outside, the latter being let in flush with the exterior surface of the cage. The upper end or bight of this strap forms a hinge-socket 6' for the latch, by passing 95 through an eye or slot 4' of said latch. This forms a simple and practical hinge, and by releasing the strap 6 the latch may readily be removed.

In order to render the operation of the 100 latch positive, I apply to it, a spring 7. This spring is a relatively long strip, the upper end of which is secured by the screws 7' to the cage, substantially flush with its exterior surface, just above the apex of the 105 wider opening 2. Said spring thence extends downwardly in the median line of said opening, and its lower slightly curved end bears upon the latch and is guided in a groove 8 in the back thereof. The tension of the spring is such that when the latch is raised to a vertical position it bears

- with greatest force, tending to positively force the latch down; and in this position, lying in the groove 8, it is flush with all exterior curvatures and presents no obstruction. The groove 8 in the back of the latch also acts, in conjunction with the spring lying in it, to hold the latch against undue lateral movement, thereby supplementing the hinge strap 6 in limiting lateral play.
- 10 In practice, as the tool finds the broken end of the sucker-rod and the coupling of said rod contacts with the under side of the latch, which thereby lifts to pass said coupling, the pressure of the spring will prevent the latch from sticking or binding on the coupling edges and will when the coupling is passed positively throw the latch down for its lifting engagement under the coupling. With this positive action of the latch, I have found in practice that my improved mouse-traps do not break nor are they returned for repairs.

In order to make the cage, when lowered, more readily find the rod and have less tendency to stick on the rod coupling, I incline the lower edge 9 of the cage to its axis, and I bevel at 10 its inner surface, as seen in Fig. 2. By slightly rotating the cage, the inclined edge will slip off the edge of the coupling and its passage will be facilitated by the bevel 10.

The suspending stem 11 of the cage I intentionally weld on that side of the cage in which lies the larger opening 2. This gives better balance to the whole tool; and in order to afford a better suspension balance, I bend said stem inwardly toward the axis of the tool, as shown in Fig. 2.

I claim:

- 40 1. A sucker-rod mouse-trap comprising an open-ended cage having openings in its walls, the bases of said openings forming seats for a swinging latch; a forked latch within said cage operating to and from said seats, said latch having a groove in its back; a detachable U-strip straddling and secured to the wall of the cage, the bight of said strip extending above the base of the wall

opening and engaging a slot in the latch to form a hinge therefor; and a spring member secured at one end to the cage and bearing and fitting at its other end within the groove in the back of the latch, said spring serving to control the latch and to hold it against lateral play.

2. A sucker-rod mouse-trap comprising an open-ended cage having one relatively wide opening in its wall on one side and two relatively narrow openings on the other side, the bases of said openings forming seats for a swinging latch; a forked latch hinged within said cage, and operating to and from said seats; a spring member controlling said latch and normally holding it closed; and a suspension stem extending from the upper end of said cage on the same side as its larger opening and bent inwardly toward its axis.

3. A sucker-rod mouse-trap consisting of an open-ended cage having one relatively wide opening in its wall on one side and two relatively narrow openings on the other side, the bases of said openings forming seats for a swinging latch; a forked latch within said cage, operating to and from said seats, said latch having a groove in its back; a detachable U-strip straddling and secured to the wall of the cage below its wide opening, the bight of said strip extending above the base of said opening and engaging a slot in the back of the latch to form a hinge for said latch; a spring member secured at one end to the cage above its wide opening and bearing and fitting at its other end within the groove of said latch; and a suspension stem extending from the upper end of said cage on the same side as its larger opening and bent inwardly toward its axis.

In testimony whereof I have signed my name to this specification in the presence of two subscribing witnesses.

MARCUS SHINSKIE.
